UNITED STATES PATENT OFFICE.

ALBERT D. AUSTIN, OF PORTLAND, OREGON, ASSIGNOR OF FORTY-FIVE ONE-HUNDREDTHS TO AUTOREST MOTOR SALES COMPANY, A CORPORATION OF OREGON, AND TWENTY ONE-HUNDREDTHS TO QUIN L. JONES, OF PORTLAND, OREGON.

CARBURETOR.

Application filed March 1, 1920. Serial No. 362,446.

To all whom it may concern:

Be it known that I, ALBERT D. AUSTIN, a citizen of the United States of America, and resident of Portland, in the county of Multnomah, in the State of Oregon, have invented certain new and useful Carburetors, of which the following is a specification, reference being had to the accompanying drawing.

My invention relates to carburetors, and 10 consists in the devices set forth in the claim for controlling the admission of air and fuel.

What constitutes my invention will be hereinafter further set forth in detail and succinctly specified in the appended claim.

15 In the accompanying drawing,

Figure I is a side elevation, partly in section, of the present preferred form of my invention, showing means for air supply and liquid fuel supply, and for co-regulating the 20 same.

Figure II is a medial vertical section, partly in elevation, of the subject matter of Figure I, taken at right angles thereto.

Referring to the numerals on the drawing, 25 1 indicates a carburetor shell shown as communicating at its upper end with a manifold 2, of which the drawing shows a fragment bolted to the shell 1. Said shell is provided with an air inlet 3 and with a throttle valve 20 preferably a butterfly valve 4, transversely mounted therein to admit, exclude, or regulate the admission of air. To the axle 5 of the valve 4 is fixed a bell-crank lever 6, one arm of which is movably secured to a rod 7 whereby the lever 6 may be actuated at a 30 point remote from it by any suitable and ordinary mechanism for the purpose not necessary to illustrate. The remaining arm of the lever 6 is pivotally connected as by a stud 8 with a sleeve 9 from which the stud projects. The sleeve 9 loosely fits a rod 10 which is threaded near one end, as indicated at 11, to accommodate nuts 12 and 14 located upon opposite sides of the sleeve 9, and adapted 35 adjustably to fix its position upon the rod 10. A set screw 15, working in a threaded aperture within a projection 16 mounted upon the shell 1, serves as an adjustable stop-piece to limit the movement of the lever 6, about the 40 axis of the member 5. The rod 10 is loosely connected as indicated at 18 to a crank arm 19 secured outside of the shell 1, to a hollow shaft 20 that is mounted in a bearing 21 in the shell, and which carries on its end within

the shell a cam 22. Coaxially mounted at one 55 end within the shaft 20 is a rock shaft 23 whose end opposite the shaft 20 is rotatably mounted in a suitable bearing 25, coaxial with the bearing 21, that is provided for it in the shell 1, and serves to afford rigid 60 alignment to both shafts 20 and 23. The shaft 23 carries a cam 26 that is fixed to it and is disposed in independently operative propinquity to the cam 22.

To the end of the shaft 23 is fixed a crank-arm 27 whose free end is loosely connected, as indicated at 28, to an actuating rod 30, by which it may be actuated substantially after the manner of the rod 7, but independently thereof.

70 The two cams, 22 and 26, are located in operative disposition to the head-piece 31 of a valve-stem 32 mounted with snug fitment within a bore provided for it in a screw plug 33 which, by the aid of an annular flange 34 or other means, makes a tight joint with the top of a head 35 that is carried upon a hollow stem 36, which is rigidly united, as by an integral close-fitting flanged annulus 37 that is secured, as by screws 38 or otherwise, to a base or annular flange 40 provided upon that end of the shell 1 that is opposite to the manifold 2. The transverse diameter of the stem 36 is relatively such as to afford a wide, clear space between it and the inner 75 wall of the enclosing shell 1.

75 Within the head 35 is provided a differential pressure chamber 41. The correlative contours of the chamber 41 and of the internal end of the plug 33 may be varied, but I 80 prefer, for economy of space, for instance, to impart to the bottom of the chamber 41 a conical shape, as indicated by 42, and to the end of the plug 33 a conical contour 45 of reduced diameter, the reduction being determined by the presence of a shoulder 46 that is, by preference in practice, substantially flush with the top wall of the chamber 41. The end of the valve-stem 32 terminates in a 85 conical valve 47 preferably of elongated gradual taper that takes into a valve-seat 48 provided for it in the truncated end of the conical wall 42. A coiled spring 49, interposed about the stem 32 between the tip of the plug 33 and the bottom of the head-piece 31 affords a constant yielding force to keep 90 the valve 47 normally separated or lifted from its seat 48.

Upon the side of the valve-seat 48, opposite the chamber 41, I provide the stem 36 with a bore 50 that is preferably formed of two transverse diameters disposed upon opposite sides of a shoulder 51 in the bore. The extremity of the bore 50, proximate to the valve-seat 48, is preferably truncately conical in shape as indicated at 52.

The presence of the bore 50 within the stem 36 is to make amply spacious provision upon the outside of it for a liquid fuel supply pipe 53 that is rigidly supported within the bore in coaxial relationship thereto as by a flanged nipple 54 into which it is preferably threaded, as indicated at 55, and which is set in spaced relationship to the open end of the bore 50 as by screw bolts 56 threaded into the end of the flanged annulus 57, through spacing sleeves 57. The free end of the pipe 53 terminates in a constricted discharge nozzle 58. An adjustable collar 59 is threaded to the perimeter of the flange of the nipple 54 to afford an annular regulator, whose adjustability permits control of the supply of outside air to the interior of the bore 50.

The head 35 in exterior contour is preferably of the bulbous or, more specifically, substantially of the lozenge shape in cross section, clearly illustrated in Figure II of the drawing. One purpose of the preferred exterior contour of the head 35 is to contribute thereby to the definition of a constricted and preferably annularly deflected passage-way 60 between the interior of the shell 1 upon opposite sides of the extreme annular projection 61 of the head 35. A bulbous enlargement of the shell 1 about said projection 61, as indicated at 62, is preferably employed as complementary to the shape of the head 35 for defining the passage-way 60.

In the head 35, and preferably in close juxtaposition to the shoulder 46 of the plug 33 when in place, I provide an annular series of minute radially disposed ducts 63 whose respective longitudinal axes are preferably substantially at right angles to the longitudinal axis of the chamber 41.

By manipulation of the respective rods 7 and 30, the shafts 20 and 23 may be made to oscillate to impart independent actuation to their respective cams 22 and 26. The rod 7 controls the throttle valve 4 and the rod 30 controls the valve 47. The rod 10 operatively connects the bell-crank lever 6

and the crank arm 19, with the effect of rendering the adjustment of the valve 47 responsive to that of the throttle valve 4. It should be noted in this connection that the working length of the cam 22 is somewhat less than that of the cam 26 and less than would suffice at any time to effect complete closure of the valve 47. The purpose therein is to provide effective means for cutting down the gasoline supply relatively to the adjustment of the throttle 4 without "killing" the engine. Adjustment of the sleeve 9, fixed by the nuts 12 and 14, affords means for regulating and determining the relative effect and degree of the movement of the valve 47 that will be occasioned by movement of the throttle 4.

By aid of my invention, the liquid fuel supply may be entirely shut off through closure of the valve 47 without being affected by the adjustment of the throttle valve. Consequently, it is made possible by my invention to eliminate any residuum or leakage of hydrocarbon within the shell 1 after the valve 47 is closed and thereby materially to reduce that deposit of carbon within the engine which such residuum or leakage occasions in carburetors hitherto known in the art.

What I claim is:

In a carburetor, a casing having an air inlet opening, a valve for said opening, means for operating said valve, a fuel delivery nozzle extending through said casing, a valve seat in said casing for controlling the passage of fuel therethrough, a fuel valve for said seat, a transverse shaft in said casing, a cam on said shaft adapted to engage and to actuate said last mentioned valve, said cam being adapted to effect only a partial closing of the said valve when given a complete movement, means for operating said cam from the air inlet valve, a second cam on said shaft above said fuel valve and adapted to completely close the valve, and means for directly and manually actuating said last mentioned cam independently of the first mentioned cam and said air inlet valve.

In testimony whereof, I have hereunto set my hand in the presence of two subscribing witnesses.

ALBERT D. AUSTIN.
